HOWARD V. HARDING, OF HUDSON, NEW YORK, ASSIGNOR TO GIFFORD-WOOD COMPANY, A CORPORATION OF NEW YORK.

TROLLEY-BUCKET-ROPE TAKE-UP.

Application filed November 26, 1926. Serial No. 150,802.

This invention relates generally to trolley bucket installations, and aims to provide means for automatically taking up the slack in the trolley rope and for maintaining the 5 rope under substantially constant tension, so that slippage of the rope on the driving drum will be minimized, while excessive strains will be obviated.

The invention may be understood by reference to one illustrative embodiment shown in the accompanying drawings, in which:

Fig. 1 is a diagrammatic view showing in elevation a trolley bucket installation equipped with a rope take-up;

Fig. 2 is a longitudinal section of the 15 take-up carriage on a larger scale;

Fig. 3 is a bottom plan view of the take-up carriage; and

Fig. 4 is a section on line 4—4 of Fig. 2, 20 showing the carriage-supporting rollers on the rail of the trolley bucket.

Because of the satisfactory service and ease of control obtainable, many trolley bucket installations employ the two rope system, wherein one power-actuated rope hoists and lowers the bucket while the other rope, which is entirely independent, causes the bucket to travel back and forth between the loading and discharge points. A typical 25 installation is shown in Fig. 1, and includes a bucket 5, a hoist rope 6 supporting the bucket, and a traverse or trolley rope 7 for effecting horizontal travel of the bucket. The hoist rope 6 is wound on the drum of an engine 8, passes over sheaves 9 of the trolley 10 and under the bucket sheave 11, and is secured as at 12 to the elevated track 13 along which the trolley travels. Hence the weight of the bucket is effective to take 35 up slack in the hoist rope. On the other hand, the trolley rope 7 is secured to the opposite ends of the trolley, as at 14, and is guided by idler sheaves to the trolley engine 15, being wrapped about the two grooved drums thereof to assure the utmost 40 traction possible.

An installation such as the one described 45 may give constant trouble because of slippage of the trolley rope. Each time the bucket is started, its inertia must be overcome by the mere frictional grip of the rope on the grooved drums. When the bucket is stopped, the braking of one or both of the drums can act only through one end of 50 the rope to stop the bucket, the momentum

of which may be very great. Slippage may be temporarily overcome by some form of screw take-up, but due to the stretching of the rope, such a take-up is quite unsatisfactory; it must be constantly adjusted, and it may put far too heavy a strain on the rope, causing further stretching of the rope and an unnecessarily heavy load on the bearings of the sheaves and drums. Furthermore, the take-up is usually up on the track, 60 where it is difficult to reach, with the result that it is not looked after often enough. The invention provides an automatic take-up, requiring no adjustments, and scarcely any attention. 70

In the illustrative embodiment of Fig. 1, the trolley rope 7 passes from the trolley around a guided idler sheave 16 and thence to the drums. Tension is put on the rope by connecting a cable 17 to the sheave and suspending a heavy weight 18 from the lower end of the cable, an idler 19 being used to guide the cable. With this arrangement, if the weight is properly selected, the correct tension will be put on the rope to insure maximum traction, and yet yielding of the rope will be permitted responsive to the jerk of a sudden start. 75

To support the idler sheave 16, a traveling carriage is provided, the details of which are shown in Figs. 2, 3 and 4. The carriage shown consists of a frame 20 carried by a bracket 21 and rollers 22 which run over the monorail or track 13. The idler sheave 16 rotates about a vertical axle 23 whose upper end is supported by the bracket 21, and anti-friction bearings 24 are preferably provided as shown. For lubrication of the sheave, a conduit 25 is secured to the lower end of the axle and extends outwardly from the carriage and has a force feed nipple 26 placed so that a supply of grease sufficient for a considerable interval of time may be forced into the bearing. To guide the trolley rope, rollers 27 are provided at one end of the carriage, and turn on a common horizontal axis, being so arranged that the rope passes from the tops of the rollers to the idler sheave substantially without deviation. 95

In operation, each time the bucket is suddenly started the take-up yields, as is evidenced by the weight which smoothly rises or falls a few inches and then returns to its normal position. In spite of this 100 105 110

movement of the carriage, the tension on the trolley rope is constant, because it is solely due to gravity. When the rope stretches, as it always does when new, no matter what material it is made of, the stretch is automatically taken care of without adjustment of any parts. The take-up is entirely independent of the bucket ropes and therefore does not move when the bucket travels, but only responsive to sudden heavy strains on the trolley rope, and then for only a few inches, without slackening of the rope tension. If the take-up ever becomes inoperative, as from breaking of the weight supporting rope, the bucket may still be hoisted and lowered. Usually such breakage may be foreseen and hence prevented. If a change in the tension is desired, it is not difficult to change the weight.

Obviously the present invention is not restricted to the particular embodiment thereof herein shown and described. Moreover, it is not indispensable that all the features of the invention be used conjointly since they may be employed advantageously in various combinations and sub-combinations as defined in the claims.

What is claimed is:

1. A trolley bucket installation comprising, in combination, an elevated track, a trolley movable along the track; a bucket supported by the trolley; a trolley rope secured to the opposite ends of the trolley; means for driving the trolley rope to cause the bucket to travel; a carriage movable along guides; a sheave mounted on said carriage; the trolley rope passing from the trolley around said sheave and thence to the driving means; and a yieldable slack take-up device connected with the sheave carriage so as to maintain the trolley rope at all times under substantially constant tension.

2. A trolley bucket installation comprising, in combination, an elevated track; a

trolley movable along the track; a bucket supported by the trolley; a trolley rope secured to the opposite ends of the trolley; means for driving the trolley rope to cause the bucket to travel; a carriage movable along the track; a sheave on said carriage; the trolley rope passing from the trolley around said sheave and thence to the driving means; and a gravity actuated slack take-up device connected with the sheave carriage so as to maintain the trolley rope at all times under substantially constant tension, and so as to yield responsive to heavy strains on the rope.

3. A trolley bucket installation comprising, in combination, an elevated track; a trolley movable along the track; a bucket supported by the trolley; a trolley rope secured to the opposite ends of the trolley; means for driving the trolley rope to cause the bucket to travel; a carriage movable along the track; a sheave on the carriage; the trolley rope passing from the trolley around said sheave and thence to the driving means; a line connected at one end with the carriage, a heavy weight at the other end of the line; and a roller supported by the track to change the direction of pull on said line, so that the trolley rope is maintained at all times under substantially constant tension.

4. A carriage for conveyor rope take-ups comprising, in combination, a frame; a sheave rotatably mounted on the frame; idler rollers carried at one end of the frame to support the rope as it passes to and from the sheave; said idlers arranged so that the rope passes thereto without contact with any part of the frame; a bracket secured to the carriage; and rollers carried on the bracket for travel on rails, whereby the carriage is guided and supported.

In testimony whereof, I have signed my name to this specification.

HOWARD V. HARDING.
